UNITED STATES PATENT OFFICE.

HERMAN H. WOLTER, OF MERIDEN, CONNECTICUT, ASSIGNOR TO EDWARD MILLER & COMPANY, OF MERIDEN, CONNECTICUT, A CORPORATION OF CONNECTICUT.

DESIGN FOR A CANOPY FOR LIGHTING FIXTURES.

Application filed June 9, 1923. Serial No. 6,453. Term of patent 7 years.

To all whom it may concern:

Be it known that I, HERMAN H. WOLTER, a citizen of the United States, and a resident of Meriden, in the county of New Haven and State of Connecticut, have invented a new, original, and ornamental Design for a Canopy for Lighting Fixtures, of which the following is a specification, reference being had to the accompanying drawing, forming a part thereof.

The figure is a side elevation of the canopy made according to my design.

I claim:

The ornamental design for a canopy for lighting fixtures as shown.

HERMAN H. WOLTER.
